(57) CLAIM

I claim the ornamental design for a novelty bottle golf tee, as shown and described.

DESCRIPTION

FIG. 1 is a perspective view of a novelty bottle golf tee.

FIG. 2 is a front elevation view thereof.

FIG. 3 is a rear elevation view thereof.

FIG. 4 is a top plan view thereof.

FIG. 5 is a bottom plan view thereof.

FIG. 6 is a right-side elevation view thereof; and,

FIG. 7 is a left-side elevation view thereof.

The broken lines in the drawings illustrate portions of the novelty bottle golf tee that form no part of the claimed design.

1 Claim, 7 Drawing Sheets
